(57) **CLAIM**

The ornamental design for a solar collector pillar, as shown and described.

DESCRIPTION

FIG. 1 is an isometric view of a first embodiment of a solar collector pillar showing the new design;

FIG. 2 is a right side view thereof;

FIG. 3 is a left side view thereof;

FIG. 4 is a front view thereof;

FIG. 5 is a back view thereof;

FIG. 6 is a top plan view thereof;

FIG. 7 is a bottom plan view thereof;

FIG. 8 is an isometric view of a second embodiment of a solar collector pillar showing the new design;

FIG. 9 is a right side view thereof;

FIG. 10 is a left side view thereof;

FIG. 11 is a front view thereof;

FIG. 12 is a back view thereof;

FIG. 13 is a top plan view thereof;

FIG. 14 is a bottom plan view thereof;

FIG. 15 is another right side view thereof;

FIG. 16 is a top cross-sectional view at the (H) position of FIG. 15;

FIG. 17 is a top cross-sectional view at the (M) position of FIG. 15; and,

FIG. 18 is a top cross-sectional view at the (L) position of FIG. 15.

The broken lines are for environmental purposes only and form no part of the claimed design. The design shown is not to be limited to any particular size and may be scaled larger or smaller.
